G. B. STRYKER, JR

ASEPTIC TANK

Filed Sept. 25, 1919

UNITED STATES PATENT OFFICE.

GEORGE B. STRYKER, JR., OF MEMPHIS, TENNESSEE.

ASEPTIC TANK.

Application filed September 25, 1919. Serial No. 326,233.

To all whom it may concern:

Be it known that I, GEORGE B. STRYKER, Jr., a citizen of the United States, residing at Memphis, in the county of Shelby and State 5 of Tennessee, have invented certain new and useful Improvements in Aseptic Tanks; and I do hereby declare the following to be a full, clear, and exact description of the invention, such as will enable others skilled 10 in the art to which it appertains to make and use the same.

The present invention relates to aseptic tanks for sanitary systems and consists in the combinations and arrangements of elements hereinafter described and particularly 15 set forth in the appended claim.

The purpose of the invention is to provide a tank of the character in question which is built of a plurality of plastic units 20 or sections assembled and secured in superposed relation to the end that such tanks, of any desired size, may be installed from one grade of stock and thereby not require several different grades or kinds for the various 25 types of buildings or dwellings in which this principle of sanitation is to be used.

The aseptic tank disclosed herein is designed primarily for use in dwellings in the 30 country or other outlying districts, and is especially adapted for use in connection with any portable sanitary system.

The invention is shown by way of illustration in the accompanying drawings 35 wherein:

Figure 1 is a side elevational view of the tank as assembled for installation.

Figure 2 is a detailed perspective view of one of the tank units or sections and.

Figure 3 an enlarged detail view showing the manner of re-enforcing the corners of the tank sections.

Referring to the construction in further detail and wherein like reference characters 45 designate corresponding parts, the tank consists of a plurality of units or sections 4 assembled in superposed relation and to the required height after the manner clearly shown in Figure 1. When in applied position the 50 aseptic tank is adapted to communicate with a second vessel or receiver 5 that is constructed preferably of plastic material reinforced by wire netting or the like. A pair

of screens 6 and 7 within the vessel 5 hold between them a mass of gravel 8 or other 55 granular substance which receives the material from the aseptic tank through the discharge pipe 9 and is itself discharged through the pipe 10, as shown.

Each unit or section 4 of the aseptic tank 60 is preferably rectangular in cross section, as shown in Figure 2, and the upper and lower edges of the section walls are formed with grooves 11 and ridges 12 respectively. It will thus be seen that when the sections are 65 superposed that the same will probably aline and with a suitable sealing material (e. g., ordinary mortar) between the meeting edges of the sections the several parts will be held in a secure and rigid manner. A bottom or 70 base piece 13 forms the foundation of the tank and a similar member 14, having a handle 15, provides the upper closure and top therefor. The tank, when installed, is provided with a partition 16' extending to 75 near the bottom thereof and for the full width of the tank and has for its purpose to provide the receiving and discharging chambers therefor as will be understood.

Each section 4 is constructed preferably 80 of concrete or other plastic material in suitable molds and in each corner has imbedded therein a pair of reinforcing material bars 16 and 17 as shown. The two bars 16 and 17 are of appreciably different length to the 85 end that the same will be disposed in break-joint relation and thus give rigidity to the middle portions of the sides of each section as will be clearly apparent from an inspection of Figure 2.

It will be obvious, of course, that different 90 forms of construction may be provided in lieu of that disclosed and described herein. And while I have shown and described certain apparatus for accomplishing the result 95 initially stated it is to be understood that I am not limited to the precise details shown but may on the other hand adopt such modifications or changes within the scope of the claim to better suit the end in view.

Having thus described my invention what 100 I claim as new and desire to protect by United States Letters Patent is:—

An aseptic tank comprising a plurality of 105 rectangular sections or units constructed of plastic material, metal re-enforcing bars em-

bedded within said sections, said bars being of right-angle construction and located with their respective angular portions at the corresponding angular portions of said sections, 5 said re-enforcing bars being of relatively different lengths and arranged in superposed horizontal rows in each of said sec-

tions, the longer length bars overlapping the shorter length bars, and said sections having inter-engaging tongue and grooved portions 10 and assembled in superposed relation, substantially as set forth.

In testimony whereof I affix my signature.

GEORGE B. STRYKER, JR.
